James H. Rickard, Harwinton, and Robert M. Brody,
Winsted, Conn., assignors to Ovation Instruments, Inc.,
Hartford, Conn.

Filed June 16, 1972, Ser. No. 263,615

Term of patent 14 years

Int. Cl. D17—03
U.S. Cl. D56—1 A

FIG. 1

FIG. 2

FIG. 4

FIG. 3

FIG. 5

FIG. 6

FIG. 7

FIG. 1 is a perspective view of a guitar body, showing my new design;

FIG. 2 is a top plan view;

FIG. 3 is a bottom plan view;

FIG. 4 is a right side elevational view;

FIG. 5 is a left side elevational view;

FIG. 6 is an end elevational view; and

FIG. 7 is an opposite end elevational view thereof.

Portions of the drawing figures are shaded to indicate contrast in appearance.

We claim:

The ornamental design for a guitar body, as shown and described.
